UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 13,303, dated September 19, 1882.

Application filed August 11, 1882. Term of patent 3½ years.

To all whom it may concern:

Be it known that I, HENRY HUNT, of Greenville, in the State of New Jersey, have invented a new and original Design for Carpets, of which 5 the following is a specification.

This invention relates to a new and original design for carpets and similar fabrics; and it consists in the novel grouping and configuration of figures hereinafter more fully described.

10 The accompanying photograph illustrates a face view of a carpet having my new design.

The background A is filled in with various irregularly shaped and disposed groups of small fret-work, mural work, and various small 15 right-lined and circular figures, as shown. Upon this ground are disposed the flower and leaf groups B, C, D, and E and several smaller sprays among the large groups.

B is a group of large flowers resembling sun-flowers arranged along a stem, which bears 20 in addition open-leaf forms and buds and bud-sprays.

C is a geranium cluster with three flower groups and a central group of leaves and scattered sprays and buds, all arranged along a 25 forking stem.

D is a thick cluster of small star-shaped

flowers springing from a bunch of long flag-like leaves.

E is a flower and leaf group arranged along 30 a common stem, having two large open flowers and drooping bud sprays and leaves.

I claim—

1. The design for carpets, consisting of the ground A, substantially as shown. 35

2. The design for carpets, consisting of the group B, substantially as shown.

3. The design for carpets, consisting of the group C, substantially as shown.

4. The design for carpets, consisting of the group D, substantially as shown. 40

5. The design for carpets, consisting of the group E, substantially as shown.

6. The design for carpets, consisting of the ground A, the groups B, C, D, and E, and 45 the intervening smaller groups, substantially as shown and described.

7. The design for carpets, consisting of the groups B, C, D, and E and the intervening smaller groups, substantially as shown.

HENRY HUNT.
